UNITED STATES PATENT OFFICE.

JOSEPH C. ROTH AND JOHN F. BERRICK, OF BUFFALO, NEW YORK.

CLOSURE OR STOPPER FOR BOTTLES OR OTHER RECEPTACLES.

1,056,217.

Specification of Letters Patent.

Patented Mar. 18, 1913.

Original application filed June 5, 1912, Serial No. 701,779. Divided and this application filed July 15, 1912. Serial No. 709,386.

To all whom it may concern:

Be it known that we, JOSEPH C. ROTH and JOHN F. BERRICK, citizens of the United States, residing at Buffalo, in the county of Erie and State of New York, have invented a certain new and useful Improvement in Closures or Stoppers for Bottles or other Receptacles, of which the following is a specification.

10 This invention relates to improvements in closures or stoppers for bottles or other receptacles.

The primary object of the invention is to provide a closure, or stopper for the opening 15 in a bottle or other receptacle which when fitted in place automatically locks itself therein and can not be removed without breaking the bottle.

This application is a division of an application filed June 5, 1912, Serial No. 701,779, for improvements in non-refillable bottles.

The invention also relates to certain details in the construction thereof which will be hereinafter described and claimed, reference being had to the accompanying drawings in which a preferred embodiment of the invention is shown.

Figure 1 is a central vertical section through a bottle having the improved 30 closure or stopper fitted in place in an opening in the bottom thereof. Fig. 2 is a transverse section through the bottle on line 2--2, Fig. 1. Figs. 3 and 4 are details of the self locking mechanism.

35 In referring to the preferred embodiment of this improvement shown in the accompanying drawings in detail, like numerals designate like parts.

The body 1 of the bottle, together with the 40 neck 2 are preferably formed in one integral piece of glass or other suitable material. In the embodiment shown, a round opening which is counter-sunk or enlarged at its lower end is formed in the bottom of the 45 bottle as shown in Fig. 1. A closure or stopper which is made of glass or other suitable material is shaped to fit snugly in the opening and consists of an upper body portion 3 which fits within the circular opening and 50 an enlarged bottom flange portion 4 which fits tightly in the bottom counter-sunk portion of the opening as shown in Fig. 1. To form a tight joint a thin annular washer 5 is fitted between the annular wall of the 55 opening in the bottle and the circular edge

of the stopper as shown in Fig. 1; a slight annular groove being formed in the wall of the opening to receive the washer 5 as indicated at 6 in Fig. 1. The closure or stopper is automatically locked in place by 60 spring pressed pins which when the stopper is in place are completely concealed and protected within the body of the bottle and the stopper as shown in Fig. 1.

Referring to Figs. 1 and 2 it will be noted 65 that a series of radial horizontal recesses 7 are formed in the outer or peripheral edge of the closure or stopper and a like series of radial horizontal recesses are formed in the inner surface of the annular wall of the circular opening in the bottom of the bottle body. The recesses in the inner surface of the annular wall are indicated by the numeral 8 and register exactly with the recesses 7 when the closure or stopper is properly 70 fitted in the circular opening in the bottom of the bottle as shown in Fig. 1.

While four of the registering sets of recesses are shown in the accompanying drawings, it should be understood that more or 75 less may be utilized as desired.

A series of coil springs 9 are arranged 80 within the inner portions of the recesses 7 and press against the inner ends of pins 10 located in the outer portions of said recesses 85 7 forcing the outer ends of the pins outwardly into the recesses 8 as shown in Figs. 1 and 2.

In fitting the closure or stopper in place 90 in the circular opening, the pins 10 are first forced inwardly against the tension of the springs and then the closure or stopper is placed in the opening and forced inwardly to the point where the recesses 8 register with the recesses 7 thereby permitting the 95 springs 9 to force the pins 10 outwardly into the recesses 8 and permanently and automatically lock the stopper in place in the opening in the bottle.

It will be observed by referring to Fig. 1, 100 that the slight annular groove formed in the wall of the opening in which the washer 5 is fitted is located exterior and interior to the enlarged outer countersunk portion and extends inwardly from the inner termination 105 of the enlarged countersunk portion to within a short distance of the recesses. The advantage of this construction is that the forcing of the closure or stopper into place in the opening in the bottle also forces the 110

washer 5 into the groove as the flanged portion of the closure or stopper presses against the outer edge of the washer thereby producing an absolutely air and water tight joint.

This improved closure or stopper may be employed in connection with a non-refilling mechanism located in the neck of the bottle as illustrated and described in the parent or 10 original application filed June 5, 1912, Serial No. 701,779, of which this present application is a division, or it may be differently located or arranged or may be altered modified or changed or some of the parts may be 15 altogether omitted within the scope of the following without departing from our invention.

In some instances it may be considered desirable to utilize the improvement in various 20 other types of receptacles and containers for the purpose of securing a permanently sealed package which cannot be opened without breaking the package.

We claim—

25 A bottle provided with an opening, the

outer portion of which is enlarged or countersunk, a closure or stopper shaped to fit snugly in said opening and having an inner body which fits within the inner portion of the opening and an outer enlarged 30 flanged portion which fits tightly in the enlarged or countersunk outer portion of the opening; the edge of the inner body of the closure or stopper and the surrounding wall of the inner portion of the opening having 35 complementary registering recesses, springs in said recesses, locking pins also located in the recesses and adapted to be forced into locking position by the springs; the wall of the opening exterior to the recesses and 40 inferior to the enlarged or countersunk portion being in part slightly enlarged to provide a narrow annular groove and a thin annular washer fitted in said groove and around the closure or stopper.

JOSEPH C. ROTH.

JOHN F. BERRICK.
